UNITED STATES PATENT OFFICE.

BENJAMIN V. KERSHNER, OF ST. LOUIS, MISSOURI, ASSIGNOR TO UNION SPECIAL MACHINE COMPANY, OF CHICAGO, ILLINOIS, A CORPORATION OF ILLINOIS.

PROCESS OF PIECING STAYS.

No. 909,608.

Specification of Letters Patent.

Patented Jan. 12, 1909.

Application filed April 30, 1908. Serial No. 430,063.

To all whom it may concern:

Be it known that I, BENJAMIN V. KERSHNER, a citizen of the United States, residing at St. Louis, State of Missouri, have invented certain new and useful Improvements 5 in Processes of Piecing Stays, of which the following is a description, reference being had to the accompanying drawing, and to the letters and figures of reference marked 10 thereon.

My invention relates to the processes of uniting the edges of two pieces of fabric in a predetermined position relative to each other, and more especially to the process of 15 uniting two strips of leather end to end, for the purpose of forming stays used in the manufacture of shoes, or the like.

Heretofore in joining strips of leather in making stays, it has been customary to feed 20 the two strips of leather end to end to a zig zag stitching machine, and unite the abutted ends of the two pieces by zig zag lines of stitching. A great deal of difficulty has, 25 however, been experienced in uniting pieces to form stays in this manner, for the reason that the operator, unless extremely skilful, could not join the pieces so that the longitudinal edges would be in alinement, the same as if the stay had been cut from one 30 piece of leather. The tendency of the sewing machine was to push back one side of the seam which had the effect of spoiling the stay, as it is imperative that the starting points of both pieces be exactly opposite, to 35 make use of the stay after it is finished. Then again, often one piece of leather would be thicker than the other, which would raise the presser foot so that the thin piece of leather would not be fed forward, and again 40 make imperfect stays.

The object of my invention is to provide a process of securing pieces of material in a predetermined position relative to each other, and consists in first temporarily securing 45 said pieces of material in the desired position, and then afterwards permanently securing said pieces.

In carrying out my invention, I have used the herein disclosed apparatus, although it 50 is obvious that said process may be carried out in other ways, and if desired may be carried out by hand.

In the drawings, Figure 1 is a detail view, partly in end elevation and partly in sec-

tion, showing an apparatus for carrying out 55 my process; Fig. 2 is a top plan view, showing the securing strip passing underneath the presser foot and the manner of holding the pieces on said securing strip; and Fig. 3 is a perspective view of the securing strip 60 with one of the pieces placed thereon.

In the drawings, 1 is a needle carried by a needle bar 2, which is preferably of the zig 65 zag stitching type; that is, so mounted as to be vibrated laterally after each vertical re- 70 ciprocation. 3 is a presser bar carrying a presser foot 4, having needle openings 5, and a keel 6. 7 is a work support, and 8 is a feed dog. All of these parts are of the usual construction, and will not need further descrip- 75 tion in this connection.

9 is the usual tray, which surrounds the bed plate of the sewing machine. At the forward end of said tray I have provided a recess in which is set a cup 10. Said cup is 75 secured in said recess by a screw 11, or by any other suitable fastening means. A roller 12 is pivotally secured to the cup 10. I have provided a guide wheel 13, which is mounted on a shaft 14, and so located as to guide the 80 edge of the securing strip passing through the cup. A similar wheel may be used for guiding the other edge of said strip. In the bottom of said cup I have provided a felt support 15. The forward side of the cup 85 is slotted at 16 for the insertion of the securing strip 17. A sponge 18 is placed in said cup and is so located as to bear upon the upper face of the securing strip 17. The securing strip is led from a roll mounted upon a 90 spindle or in any other suitable way, beneath the machine, up through the slot 16 in the cup, over the felt support 15 between the rollers 13, 13, and over the roller 12, and thence to the feed of the sewing machine. 95 Said securing strip 17, as shown in Figs. 2 and 3, is preferably a narrow strip, somewhat wider than the width of the zig zag seam. Said strip is provided on the upper surface with an adhesive material, and as 100 said adhesive material passes underneath the sponge 18, which, of course, is kept moist, the same will be moistened. It will be noted, therefore, that the strip is perfectly dry as it passes in front of the machine, and for this reason there is no danger of soiling the operator's hands or clothing.

The moistening cup is located at the front

of the tray 9, and, therefore, at some little distance from the stitching point, so that as the securing strip 17 leaves the roller 12, some little time elapses before it reaches 5 the stitching point. During this period of time, the operator places upon said strip the pieces of material to be stitched in the exact position it is desired to secure said pieces.

10 As shown in Fig. 2, the pieces A and B are placed end to end, so that the longitudinal edges are in alinement, and are then pressed down upon the moist adhesive material, which quickly sets and temporarily secures 15 said pieces in this position. The strip then carries the pieces forward underneath the presser foot, and the keel 6 engaging the meeting edges of the strips, will properly guide the same between the needles, so 20 that said edges will be secured permanently by the zig zag stitches 19, as shown in Fig. 2.

In view of the fact that the pieces are secured temporarily in the exact position in which they are to be stitched, it will be seen 25 that they will be carried forward in this position to the stitching mechanism. If one of the pieces should be thicker than the other, it is immaterial, for the reason that the securing strip is carried forward by the 30 feed of the machine, and serves to carry forward the pieces which are to be stitched.

It is obvious that the pieces, if desired, may have their edges slightly overlapped, or 35 may be arranged at any other desired position, and temporarily secured by the adhesive strip, and that they may then be fed to the stitching mechanism and secured in the position in which they have been placed.

It is obvious that any other form of stitching mechanism may be used for that herein 40 shown, without in any way departing from the spirit of my invention. In fact, the apparatus herein shown, may be varied in many ways, without in any manner changing 45 my process.

By using a paper adhesive securing strip, the stays may be readily cut apart on a line coincident with the longitudinal edges of the stay, leaving a clean cut edge, while with a 50 cloth securing strip the thread ends or whiskers are liable to extend beyond the cut edge.

Having thus described my invention, what I claim as new and desire to secure by Letters Patent, is:—

55. 1. The process of uniting two pieces of fabric in a predetermined position relative

to each other, consisting in placing said pieces in the desired relation to each other on a strip of adhesive material, whereby they are temporarily secured, then feeding said 60 pieces with the securing strip to a stitch-forming mechanism, whereby the pieces may be firmly secured by stitching.

2. The process of uniting the edges of two pieces of fabric in a predetermined position 65 relative to each other, consisting in placing the ends of said pieces in the desired relation to each other on a strip of material and temporarily securing them thereto, then feeding said pieces with the securing strip to a stitch-forming mechanism, whereby the pieces may 70 be firmly secured by stitching.

3. The process of uniting the edges of two pieces of fabric in a predetermined position 75 relative to each other, consisting in placing said strips with their ends abutted, and their longitudinal edges in alinement on a strip of adhesive material, whereby they are temporarily secured, then feeding said pieces with the securing strip to a stitch-forming 80 mechanism, whereby the pieces may be firmly secured by stitching.

4. The process of uniting the edges of two pieces of fabric in a predetermined position 85 relative to each other, consisting in feeding a strip of adhesive material to a stitching mechanism, moistening said strip, placing the pieces of fabric upon said strip in the desired position, whereby they are temporarily secured, and then carried with the 90 adhesive strip to the stitching mechanism, where they may be firmly secured by stitching.

5. The process of uniting two pieces of 95 fabric in a predetermined position relative to each other, consisting in placing said pieces in the desired relation to each other on a strip of adhesive material, whereby they are temporarily secured, then feeding said pieces with the securing strip to a stitch-forming mechanism, whereby the pieces may be firmly secured by stitching, and then cutting the strip of adhesive material on a line coincident with the longitudinal edges 100 of the pieces of fabric.

In testimony whereof I affix my signature, in presence of two witnesses.

BENJAMIN V. KERSHNER.
